UNITED STATES PATENT OFFICE

2,119,311

TRIPE WASHER

Oscar Biedermann, Chicago, Ill., assignor to The
Globe Company, Chicago, Ill., a corporation of
Illinois

Application June 22, 1937, Serial No. 149,711

8 Claims. (Cl. 17—43)

This invention relates to tripe washers. Washers of the character forming the subject matter of this specification are used for washing and scrubbing tripe and similar articles of food.

5 Heretofore a rotatory or oscillatory cylinder or drum has been employed for this purpose, and the scrubbing wall thereof usually was formed with a multiplicity of holes, surrounded by inwardly struck-up burrs, the edges of which were 10 rough and served to wear away offensive matter from the tripe as it tumbled about in the rotatory or oscillatory cylinder. The cylinder rotated or oscillated in a tub containing water, soda or some other cleansing substance which entered 15 the cylinder through the holes in its scrubbing wall and washed away the foreign matter.

The main difficulty with cylinders of this construction, has been that the burrs wear away rapidly and after the machine has been in use 20 for a relatively short time the cylinder must be replaced. This adds greatly to the cost of processing the tripe and often the cylinder must be discarded, although many of the burrs are still in a fairly good condition for use.

25 The principal object of the present invention is to provide removable and replaceable burrs for the cylinder, whereby when any of them become worn down so as to be practically useless, the worn burrs may be removed from the cylinder and replaced by new ones, thereby enabling the cylinder to be used for an indefinite length of time.

Another object is to provide burrs for the cylinders of tripe washers, which may be easily and 35 quickly removed from the cylinder and replaced by new ones.

With these and other objects and advantages in view, this invention consists in the several novel features hereinafter fully set forth and 40 claimed.

45 The invention is clearly illustrated in the drawing accompanying this specification, in which:—

Fig. 1 is a side elevation, partly broken out, of a tripe washer, embodying a simple form of the 50 present invention;

Fig. 2 is a side elevation of the cylinder, partly broken away;

Fig. 3 is an enlarged, fragmental plan of the cylinder scrubbing wall showing one of the burrs 55 secured therein;

Fig. 4 is a vertical, longitudinal section, taken on the line 4—4 of Fig. 3, and

Fig. 5 is an enlarged central section through a slightly modified form of burr.

55 Referring to said drawing, the reference char-

acter 5 indicates the tub of a standard make of tripe washer, usually in the form of a semi-cylindrical tub, mounted on legs at each end, two of which are shown at 6. Rising from the rear part of the tub is a stationary cover 7, which leaves 5 an opening at the front, that is closed by a movable cover 8. Desirably the tub is reenforced by a frame 9. A discharge trough 10 is usually provided at the bottom of the tub, which is controlled by a valve or gate (not shown) operated 10 by a lever 11.

Rotatively mounted in the tub is a container 12 for the material to be washed. It is shown in the form of a cylinder composed of end walls 13, connected by a scrubbing wall 14. Stub shafts, 15 one of which is seen at 15, are secured to the end walls of the cylinder, and are journaled in bearings carried by the frame. Means are provided to rotate or oscillate the cylinder, the means shown comprising a wheel or pulley 16 mounted on one of the shafts, a wheel or pulley 17, driven by an electric motor 18, and a belt 19 trained around the wheels or pulleys. The motor is mounted on a frame 20 carried by the tub or its stationary cover. The driving means shown 25 serves to rotate the cylinder in the tub.

The scrubbing wall 14 is usually made of sheet metal, and may take various shapes. It may be cylindrical or many sided, and it is here shown as formed of concavo-convex sections 21, secured upon rods 22, fastened to the end walls. 30 The convex faces of the sections 21 form the internal faces of the scrubbing wall, in the form of the invention shown. The section 23 closes an opening 24, in the scrubbing wall, through which the material to be washed is placed in the cylinder and through which the cleaned material is 35 removed. The section 23 may be hinged to the rod 22, at one side of the opening, and is provided with a latch 25 for locking it to the rod 22 at the 40 other side of the opening. These parts are common and well known and require no further description so far as this specification is concerned.

In the several sections of the scrubbing wall, 45 holes 26 are punched, and in said holes are secured removable and replaceable burrs 27, which project into the interior of the cylinder. As shown, the burrs are in the form of sheet metal stampings, struck up with suitable dies. Desirably the burrs are of ring like or annular form, having a cylindrical web 28, which projects laterally from the outer margin of a round flat web 29, and a cylindrical web 30, which projects laterally in the opposite direction from the inner margin of the web 29. The cylindrical web 28 projects into 50 55

the interior of the cylinder, and its edge is roughened, serrated or otherwise shaped to enable the burr to operate on the tripe with an abrading action, as the latter tumbles about in the cylinder.

5. As shown, the edge portion of the cylindrical web 28 is struck up outwardly to form a multiplicity of scallops 31, the lower ends of which merge into the cylindrical part of the web. The edges of the scallops and of the cylindrical parts therebetween, provide variously directed abrading edges, thereby greatly increasing the efficiency of the burr.

The round web 29 lies flush with the inner face of the scrubbing wall, and the cylindrical web 30 projects through the hole 26, and has its edge portion 32 clenched upon or beaded over the metal of the scrubbing wall adjacent the hole. Desirably the burrs are secured to the scrubbing wall by means of a suitable tool or die. In case 20 a burr becomes worn down to such an extent that it does not function properly, the beaded part 32 is collapsed, permitting the burr to be removed and replaced by a new one.

In the modified form of burr illustrated in Fig. 25 5, the burr 27^a is formed with the cylindrical web 28^a, the round flat web 29^a and the smaller cylindrical web 30^a, as in the preferred form, but the scrubbing edge of the burr is serrated as shown at 31^a. In other respects the burr is similar to the one heretofore described and is attached to the cylinder in the same manner.

In the operation of the washer, the tub is filled, or partially filled with water and cleansing material and the tripe or other material is placed 35 on the cylinder and the latter operated in the usual manner.

By reason of the scalloped abrading edges of the burrs, a more efficient abrading action is obtained on the material and there is no likelihood 40 of its being injured, as is the case when the ordinary burrs are used. Moreover, the burrs may be made from non-corrosive material, having good wearing properties, thereby prolonging their usefulness far beyond that of the ordinary burrs that 45 are struck up from the material of the scrubbing wall.

I claim as new and desire to secure by Letters Patent:

1. In a washer of the class described, the combination of a container having a scrubbing wall formed with a multiplicity of holes therein, and removable and replaceable burrs secured to said wall around said holes, said burrs having roughened scrubbing edges.

5. 2. In a washer of the class described, the combination of a cylinder having a scrubbing wall formed with a multiplicity of holes therein, and burrs removably and replaceably secured to said

wall around said holes, said burrs having serrated webs projecting into the interior of the cylinder and having other webs extending through said holes and clenched upon the outer face of said wall.

3. In a washer of the class described, the combination of a container, having a scrubbing wall formed with a multiplicity of holes therein, and removable and replaceable burrs, each having a web projecting into the interior of the container, the edge of which web is scalloped, each burr having also a web extending through a hole and clenched upon the outer face of the wall, and there being a web connecting said other webs and being seated on said wall.

4. In a tripe washer, the combination of a container having a scrubbing wall formed with a hole therein, an annular removable and replaceable burr surrounding said hole and clenched to the material of the wall adjacent the hole, said burr 20 having an annular web projecting into the interior of the container and formed with a scalloped edge.

5. In a tripe washer, the combination of a container having a scrubbing wall formed with a round hole, and an annular removable and replaceable burr having a round web seated on the wall adjacent the hole, and a cylindrical web extending from said round web through the hole and beaded over and upon the outer face of said 30 wall, there being an annular web projecting from said round web into the interior of the container and formed with an irregular edge.

6. In a tripe washer, the combination of a container having a scrubbing wall formed with a round hole, and an annular removable and replaceable burr having a round web seated on the wall adjacent the hole, and a cylindrical web extending from said round web through the hole and beaded over and upon the outer face of said 40 wall, there being an annular web projecting from said round web into the interior of the container and formed with a scalloped edge.

7. In a tripe washer, a scrubbing wall having a hole therein, and a removable and replaceable 45 annular burr surrounding said hole and clenched to the scrubbing wall, the burr having an annular scrubbing member projecting from one side of the scrubbing wall, and formed with a roughened scrubbing edge.

8. In a tripe washer, a scrubbing wall having a hole therein, and a removable and replaceable annular burr surrounding said hole and clenched to the scrubbing wall, the burr having an annular scrubbing member projecting from one side of 55 the scrubbing wall and having a scalloped scrubbing edge.

OSCAR BIEDERMANN.
